RECORD RACK

Lewis Davis, 114-116 Charing Cross Road,
London, England

Filed Nov. 1, 1963, Ser. No. 77,234

Term of patent 7 years

(Cl. D33—3)

Fig. 1.

Fig.2.

Fig.3.

The side of the record rack not shown has the same configuration as the illustrated side.

I claim:

The ornamental design for a record rack, substantially as shown and described.
